(57) **CLAIM**

The ornamental design for the rattling soccer ball noisemaker, as shown and described.

DESCRIPTION

FIG. 1 shows an isometric view of a first embodiment of the rattling soccer ball noisemaker, which excludes the eyelet that is shown in phantom lines for illustrative purposes;

FIG. 2 shows a top plan view of the rattling soccer ball noisemaker of FIG. 1;

FIG. 3 shows a bottom plan view of the rattling soccer ball noisemaker of FIG. 1;

FIG. 4 shows a front elevation view of the rattling soccer ball noisemaker of FIG. 1;

FIG. 5 shows a back elevation view of the rattling soccer ball noisemaker of FIG. 1;

FIG. 6 shows a left side elevation view of the rattling soccer ball noisemaker of FIG. 1;

FIG. 7 shows a right side elevation view of the rattling soccer ball noisemaker of FIG. 1.

FIG. 8 shows an isometric view of an alternate embodiment of the rattling soccer ball noisemaker, which includes the eyelet;

FIG. 9 shows a top plan view of the rattling soccer ball noisemaker of FIG. 8;

FIG. 10 shows a bottom plan view of the rattling soccer ball noisemaker of FIG. 8;

FIG. 11 shows a front elevation view of the rattling soccer ball noisemaker of FIG. 8;

FIG. 12 shows a back elevation view of the rattling soccer ball noisemaker of FIG. 8;

FIG. 13 shows a left side elevation view of the rattling soccer ball noisemaker of FIG. 8; and,

FIG. 14 shows a right side elevation view of the rattling soccer ball noisemaker of FIG. 8.
